(57) **CLAIM**

The ornamental design for a recessed frame for mounting dispensers, as shown.

DESCRIPTION

FIG. 1 is a top, front and side perspective view of a recessed frame for mounting dispensers, showing our new design;

FIG. 2 is a front elevational view thereof;

FIG. 3 is a view thereof from the right of FIG. 2;

FIG. 4 is a view thereof from the left of FIG. 2;

FIG. 5 is a top plan view thereof;

FIG. 6 is a rear elevational view thereof; and,

FIG. 7 is a view thereof from the bottom of FIG. 2.
